UNITED STATES PATENT OFFICE.

PHILIP A. LUCKETT, OF SALISBURY, MARYLAND.

UNION-PAJAMAS.

1,267,677.

Specification of Letters Patent. Patented May 28, 1918.

Application filed November 13, 1916. Serial No. 131,047.

To all whom it may concern:

Be it known that I, PHILIP A. LUCKETT, a citizen of the United States, residing at Salisbury, in the county of Wicomico, State 5 of Maryland, have invented certain new and useful Improvements in Union - Pajamas; and I do hereby declare the following to be a full, clear, and exact description of the invention, such as will enable others skilled in 10 the art to which it appertains to make and use the same.

This invention relates to union suits and has special reference to a union pajama suit embodying a drop seat and a closed crotch 15 trouser or lower section combined in a unitary structure with a waist or upper section, the whole being so arranged as to prevent any undesired exposure of the person wearing the suit.

20 I have found by experience that such union suit constructions as are embodied in the patent granted to me Oct. 12, 1915, and bearing the Number 1,156,301 are inapplicable for use in the construction of pajamas by 25 reason of the fact that a pajama suit forms practically an outer garment and in consequence must be constructed in such manner as to be closed throughout, no matter what movement or position the wearer may make 30 or assume.

I have also found that many of the features which are desirable in union undergarments are equally desirable in union pajamas. For instance, it is desirable that the 35 lower or bottom edge of the back of the waist member extend diagonally across the body from one side thereof to the other, but, in contradistinction to undergarments this diagonal bottom edge must have its lower 40 corner fixed and the drop flap must not have its opening extend below this lower corner of the bottom edge as otherwise exposure of the person would result. The diagonal arrangement of the bottom edge prevents the 45 rumpling up of the back bottom through the movements of the wearer when asleep and in this manner prevents the uncomfortable collection of the material in ridges or folds.

It is furthermore to be noted that, while 50 in undergarments such as that disclosed in my prior patent above identified no objection exists to the occurrence of a slit down one side of the garment leg, yet in pajama suits such a slit would be objectionable on 55 account of the undesirable exposure afforded thereby.

The principal object of the present invention is to provide a union pajama suit which will have all of the advantages incident to such a construction as is embodied 60 in my prior patent aforesaid and at the same time will eliminate such features of that type of suit objectionable in a pajama suit and will afford complete protection to the person of the wearer against undesirable exposure. 65

With the above and other objects in view, as will be hereinafter apparent the invention consists in general of certain novel details of construction and combinations of parts 70 hereinafter fully described, illustrated in the accompanying drawing, and specifically claimed.

In the accompanying drawing, like characters of reference indicate like parts in the 75 several views, and:—

Figure 1 is a front view of a pajama suit constructed in accordance with this invention.

Fig. 2 is a rear view of such a suit, the 80 back of the waist being made in a single piece and the seat flap shown closed.

Fig. 3 is a view similar to Fig. 2 with the seat flap open.

Fig. 4 is a view of the back waist piece as 85 constructed in two parts.

Fig. 5 is a section on the line 5—5 of Fig. 3.

Fig. 6 is a section on the line 6—6 of Fig. 4. 90

In the embodiment of the invention herein illustrated it is to be noted that the garment disclosed is of a type having the arms and legs of the length usual in what are known as athletic garments, that is to say 95 about elbow and knee length respectively. It will be obvious, however, that these lengths are purely arbitrary and that the arms and legs may be made of any desired length without affecting those parts of the 110 suit wherein the invention is directly embodied.

In these drawings it will be seen that, in the form illustrated my improved garment is made up in different sections, the sections A and B being the front sections and each extending from the neck and shoulder to the bottom of the leg. At C is shown the back section while at D are the arm sections and at E are the two back leg sections. The 110 back section C may either be made integral and provided with a reinforcing band 10 at

the waist line or it may be made in two parts, an upper part 11 and a lower part 12 connected at the waist line and reinforced by a band 13.

5 The upper parts of the sections A and B are connected together by suitable buttons and buttonholes, indicated at 14 while at the crotch of the garment these sections are united by stitching 15 to form a closed 10 crotch, the front members being also connected to the lower back leg portions by stitching 16 along the inseam. These lower back leg members are connected together by stitching 17 which runs from the crotch to 15 the waist band 18. These lower back leg members are connected to the front members along the outside of the leg by stitching 18 on one side and 19 on the other, being noted that the stitching 18' extends from the waist 20 band to the bottom of the leg while the stitching 19 extends only from the bottom of the leg to a point indicated at 20, thus leaving one side free from the leg in order to make a drop flap 21. The rear part of the 25 waist band is stitched to the reinforcing band a short distance across the back from the seam 19 as indicated at 22 and the free portion of the waist band 18 and back leg member from the point 20 is detachably connected to the front leg member and reinforcing band as by buttons and buttonholes 23.

Unless provision was made this construction would leave a gap or slit along the outside of one leg from the point 20 to the waist band, but in order to eliminate this gap and prevent exposure of the person the back member is carried down below the waist on the side opposite the gap, as to a point 24 and the lower edge of the back extends diagonally downward across the entire width of the back to the point 20, the lower or bottom edge being indicated at 25 and having a reversibly curved form so as to provide a bottom flap portion 26 extending down from 40 the waist band and a rear leg portion 27 extending inward behind the leg from the side seam and being connected to the front member by stitching 28. This provides a portion over which the drop flap laps to a substantial 45 extent so that no gaps or slits giving exposure of the person obtain along the leg.

For the purpose of tightening the gar-

ment along the waist a suitable belt 29 running through loops 30 is preferably provided.

55

From the foregoing it will be seen that the garment provides a closed crotch construction wherein no exposure of undesirable character is possible.

There has thus been provided a simple and 60 efficient device of the kind described and for the purpose specified.

Having thus described the invention, what is claimed as new, is:—

A union garment, including, below the 65 waist-line, two overlying back members each of which extends from one side seam of the garment to the other, the lower member consisting of a blank having an upper edge coextensive with the waist-line, a side edge 70 along one side seam extending to a point near the lower end of the corresponding leg and connected thereto at the side seam only, a comparatively short side edge along the opposite side seam, and a lower edge determined by an irregular curve extending 75 from the lower end of the short edge to the lower end of the long edge and defining a hollowed out portion across the middle of the garment, and the upper member consisting of a blank substantially coextensive with the back of the garment below the waist-line and having that vertical edge corresponding to the short edge of the lower member, fastened throughout the length of the side 80 seam, its upper edge attached along the waist-line to permanently overlie for a short distance the short portion of the lower member and its opposite vertical edge secured from the lower end of the long edge of the 85 lower member to the lower end of the leg, the remainder of the upper blank constituting an upwardly closing portion which will cover said hollowed out portion and provide double folds of the garment around the 90 edges of the latter opposite all points where the upper member is unattached.

In testimony whereof, I affix my signature, in the presence of two witnesses.

PHILIP A. LUCKETT. 100
